CLAIM

We claim the ornamental design for an insert for footwear, as shown and described.

DESCRIPTION

FIG. 1 is a first perspective view of an insert for footwear showing our new design;

FIG. 2 is a second perspective view thereof;

FIG. 3 is a front view thereof;

FIG. 4 is a rear view thereof;

FIG. 5 is a side view thereof;

FIG. 6 is a side view of the opposite side of FIG. 5; and,
 FIG. 7 is a bottom view thereof.

The broken lines shown in the drawings illustrate portions of the insert for footwear that form no part of the claimed design.

1 Claim, 5 Drawing Sheets
